US00D729616S

(12) **United States Design Patent**
Rothbaum et al.

(10) **Patent No.:** **US D729,616 S**
(45) **Date of Patent:** **** May 19, 2015**

(54) **STRAP FOR CORD MANAGEMENT**

(71) Applicant: **CJD LLC**, New York, NY (US)

(72) Inventors: **Wayne Rothbaum**, New York, NY (US);
Allison S. Conner, Brooklyn, NY (US);
Robert B. Curtis, San Francisco, CA
(US); **Jonas K. Damon**, New York, NY
(US); **Daniel A. Sanchez**, Brooklyn, NY
(US)

(73) Assignee: **CJD LLC**, New York, NY (US)

(**) Term: **14 Years**

(21) Appl. No.: **29/491,146**

(22) Filed: **May 16, 2014**

Related U.S. Application Data

(63) Continuation of application No. 29/458,903, filed on Jun. 24, 2013, now Pat. No. Des. 708,505, which is a continuation of application No. 29/428,997, filed on Aug. 6, 2012, now Pat. No. Des. 685,254, which is a continuation of application No. 29/368,755, filed on Aug. 27, 2010, now Pat. No. Des. 667,291.

(57) **CLAIM**

The ornamental design for a strap for cord management, as shown and described.

DESCRIPTION

FIG. 1 is a perspective view of our new design of a strap for cord management.

FIG. 2 is a top view of FIG. 1.

FIG. 3 is a bottom view of FIG. 1.

FIG. 4 is a view of a first side of FIG. 1.

FIG. 5 is a view of a second side of FIG. 1.

FIG. 6 is a view of a third side of FIG. 1.

FIG. 7 is a view of a fourth side of FIG. 1.

FIG. 8 is a perspective of FIG. 1 shown in an alternate configuration of use with an object; and,

FIG. 9 is perspective view of FIG. 1 shown in another alternate configuration of use with an object.

The broken lines showing elements of the strap for cord management and an environment of use are included for illustrative purposes only and form no part of the claimed design.

1 Claim, 6 Drawing Sheets
